[57] **CLAIM**

The ornamental design for a windshield visor for motor vehicles, as shown and described.

DESCRIPTION

FIG. 1 is a perspective view of a windshield visor for motor vehicles showing my new design, it being understood that the broken lines are for illustrative purposes only;

FIG. 2 is an enlarged top plan view thereof;

FIG. 3 is an enlarged bottom plan view thereof;

FIG. 4 is an enlarged front elevation view taken thereof;

FIG. 5 is an enlarged rear elevation view thereof; and,

FIG. 6 is an enlarged elevation view taken from one end thereof.

It should be appreciated that the mirror image of FIG. 6 is an elevation view of the opposite end thereof.
